UNITED STATES PATENT OFFICE

2,428,227

BAG AND CLOSURE THEREFOR

Nathan Kase, Binghamton, N. Y.

Application November 6, 1943, Serial No. 509,220

1 Claim. (Cl. 150—3)

1

This invention relates to improvements in bags of the kind in which the walls of the mouth of the bag are made of fabric, leather or other flexible material.

The primary object of the invention resides in a bag which is self locking to eliminate the use of frames, slide fasteners, catches, and other extraneous closure devices.

Another feature of the invention relates to a bag in which the free top edges along the opposed side walls of the bag are provided with reinforced beads for releasable interlocking engagement when the bag is in closed position and which interlocking is sufficient to prevent the bag from accidentally opening during ordinary handling of the same, but an operator may by a slight flexing of the beaded edges, cause the same to be readily disengaged when access to the interior of the bag is desired.

A further feature of the invention is the provision of a simple and inexpensive bag closure construction which may be embodied in coin purses, cosmetic bags, tobacco pouches and other like articles having an opening to be closed.

Other novel features of the invention will become apparent as the following specification is read in conjunction with the accompanying drawing, in which:

Figure 1 is a front elevational view of the invention embodied in a cosmetic bag shown in closed position, a portion of the front wall being broken away.

Figure 2 is an end elevational view illustrating the bag in open position in dotted lines.

Figure 3 is an enlarged vertical transverse sectional view on the line 3—3 of Figure 1.

Figure 4 is a front elevational view of the bag turned inside-out.

Referring to the drawing by reference characters, the numeral 10 designates the improved bag in its entirety which includes a bag body 11 constructed of flexible material such as fabric, leather, rubberized material, or the like. The bag body 11 is constructed of an outer thickness of flexible material 12 and an identically shaped thickness of inner lining material 13. The front wall 14 of the bag body has an arcuate shaped top edge 15 bound by a strip of binding tape 16 stitched to the edge 15 as at 17 to provide a tubular covering for a flexible reinforcing element 18 in the form of a length of stiff stranded or solid cord which is round in cross section as best illustrated in Figure 3. The reinforced top edge of the front wall defines an inwardly facing bead A for interlocking engagement with a com-

2

panion inwardly extending bead B provided on the top edge of the rear wall 19 and which will now be specifically described.

The top edge 20 of the rear wall 19 extends beyond the plane of the edge 15 of the front wall and is likewise convexly curved and has a length of binding tape 21 stitched thereto as at 22 for enclosing a flexible reinforcing element 23' similar to the reinforcing element 18. The ends of the edges 15 and 20 are so cut as to provide a clearance between the end portions of the beads A and B when the bag is closed, while the mid-portions thereof are disposed relative to each other to require the bead A to be forcibly pushed to a position inwardly of the bead B into interlocking engagement.

The beads A and B provide a "snap-frame" for the opening to the bag and they are secured together adjacent their ends by stitching 23 and 20 which points of stitching provide a hinge connection between the beads and the upper portion of the front and rear walls to enable the said portions to be swung to an open and closed position as illustrated in full and dotted lines in 15 Figure 2. When the bag is in closed position the entire length of the bead B overlaps the bead A but at the mid-portions, the beads A and B definitely interlock for the said mid-portions are disposed one in the path of pivotal closing movement of the other. The reinforcing elements 18 and 23 are sufficiently stiff when bowed to provide a resiliency to maintain the beaded edges in a definite shape and are capable of being flexed to enable the mid-portions of the beads A and B to pass each other when the bag is closed, whereupon the reinforcing elements spring back to normal position and effect an interlocking of the beads sufficient to prevent the open mouth of the bag from accidentally opening. The lapping beads provide a closure which prevents thin articles placed in the bag from accidentally slipping therebetween during the ordinary handling of the bag.

The bag 10 is made inside out as illustrated in Figure 4, with the lining side 13 face out. The material or thicknesses of material from which the bag is constructed is folded upon itself along the bottom fold 24 while the side edges are stitched together by the lines of stitching 23, 45 the top terminal ends of which hingedly connect the ends of beads A and B together. The tubular bindings 16 and 21 and the reinforcing elements 18 and 23' are applied while the bag is inside out and the same project beyond the stitched side edges, however, when the finished

bag is reversed, that is, turned right side out, the top corner edges of the bag are pulled inwardly as illustrated best in Figure 1, whereupon the extending ends of the beads A and B are concealed within the body of the bag.

For preventing accidental disconnecting of the interlocking beads A and B when bulky articles are placed in the bag, I provide an auxiliary fastening means in the form of a flap 25 secured at the mid portion of the top of the rear wall 19 by the stitching 22. The flap is provided with a female snap fastener element 26 which interlocks with a male snap fastener element 27 secured to the exterior of the front wall 14. The flap 25 is folded forwardly and downwardly over the interlocked portions of the beads A and B and secured by engaging the female fastener element 26 with the male fastener element 27. The flap 25 tightly fits over the beads and prevents accidental disengagement thereof by bulky articles placed within the bag which might cause the walls of the bag to unduly spread.

While I have shown and described what I consider to be the preferred embodiment of my invention, I wish it to be understood that such changes in design and details of construction as come within the scope of the appended claims may be resorted to if desired without departing from the spirit of the invention.

Having thus described the invention, what I claim as new and desire to secure by Letters Patent of the United States is:

A bag comprising a flexible body having an open mouth, the top of which is defined by a pair of convexly curved top edges, flexible solid round beads provided on the opposed edges of the

walls of the mouth and conforming to the lengthwise shape thereof and extending inwardly in confronting relation, each of said beads including a fabric tube and a length of cord enclosed within said tube and extending the length thereof, the ends of the opposed beads being connected together by stitching to provide a hinge connection between the opposed walls of the mouth, said beads being offset vertically relative to each other, the opposed end portions of the beads beyond the hinges being clear of each other and the intermediate portions thereof between the hinges overlapping when brought together to closed relation, whereby the friction between the opposed intermediate portions will effect an interlocking of the intermediate portions to secure the walls of the mouth of the bag closed, with the end portions of the beads in close overlying relation.
